(57) **CLAIM**

The ornamental design for a storage bag for wet articles as shown and described.

DESCRIPTION

FIG. 1 is a bottom plan view of a storage bag for wet articles in an opened, unzipped configuration, in accordance with the present disclosure;

FIG. 2 is a top plan view thereof;

FIG. 3 is a left side elevation view thereof;

FIG. 4 is a right side elevation view thereof;

FIG. 5 is a rear elevation view thereof;

FIG. 6 is a front elevation view thereof;

FIG. 7 is a facing view thereof, in an alternate position comprising a zipped configuration;

FIG. 8 is a rear view thereof, in the alternate position comprising the zipped configuration; and,

FIG. 9 is a front perspective view thereof, in zipped configuration.

The broken/dashed lines in FIGS. 1-9 show environment and form no part of the claimed design.

1 Claim, 6 Drawing Sheets
